UNITED STATES PATENT OFFICE.

CHARLES L. LATIMER, OF FORT WADSWORTH, NEW YORK.

VALVE-GRINDER.

1,279,370.

Specification of Letters Patent. Patented Sept. 17, 1918.

Application filed December 5, 1917. Serial No. 205,507.

To all whom it may concern:

Be it known that I, CHARLES L. LATIMER, a citizen of the United States, and a resident of Fort Wadsworth, in the county of 5 Richmond and State of New York, have invented a new and Improved Valve-Grinder, of which the following is a full, clear, and exact description.

My invention relates to grinding tools, 10 and has reference more particularly to a mechanism for grinding a valve mechanically in place of manually.

An object of the invention is to provide 15 a compact mechanical drive which can be easily accommodated on the head of a cylinder of an internal-combustion engine for engaging the valve to be ground without interference with the other parts located on the head.

20 Another object of the invention is to provide a device the oscillating stroke of which may be varied so that the valve to be ground may be rotated through angular distances of varying degrees.

25 With the above and other objects in view, the nature of which will more fully appear as the description proceeds, the invention consists in the novel construction, combination and arrangement of parts as herein 30 fully described, illustrated and claimed.

In the accompanying drawings, forming part of the application, similar characters of reference indicate corresponding parts in both views.

35 Figure 1 is a cross section through the device embodying my invention; and

Fig. 2, a vertical section on line 2—2, Fig. 1, illustrating the device in use.

Referring to the drawings, 3 is a valve- 40 engaging head having a stem 4 the upper part of which is revolvably mounted in a housing 5 which carries a ball-bearing socket 6 at the bottom. The stem carries a cone 7 which is constrained to move with the stem 45 and which coöperates with the ball-bearing socket 6. The stem 4 above the cone is provided with a dented portion 8 forming a pinion. A rack 9 is mounted to slide in a guide 10 secured to the wall of the housing 5, so that said rack is caused to slide transversely of the stem and meshes with the pinion 8. The rack 9 has a pin 11 which is connected to a crank pin 11' by a rod 12.

50 The crank pin 11' is mounted eccentrically in a carrier 13 which is revolvably

mounted in a suitable recess provided near the margin of a driving disk 14. The disk is constrained to revolve with a stub shaft 15 which bears in a collar 16 extending from the side wall of the housing 5. A handle 17 extends from the collar and it accommodates a shaft 18 to which a flexible shaft 18' may be secured at the end of the handle. The flexible shaft 18' may be driven from any suitable motor.

60 Rotation imparted to the disk 14 will reciprocate the rack 9 and, in consequence, turn the stem 4 forth and back. The angular displacement of the stem may be varied by changing the position of the crank pin 11' relative to the center of the disk by turning the carrier 13 in its recess.

65 Pressure on the valve during the grinding is maintained by a spring 19 mounted on the stem. One end of the spring rests on the 70 head 3 while the other engages a ball-bearing race 20 which is free from the stem. The stem terminates in a ball-shaped head 21 which is engaged in a socket 22. The socket has an extension through the top of 75 the housing 5 terminating with a ring 23, which can be easily engaged by the hand and whereby the stem, with the head, may be raised against the resistance of the spring 19 and, therefore, relieving pressure from 80 the valve 24.

85 To adapt the device to engines of different construction, I provide the housing 5 with a sleeve 25 mounted to telescope on the housing and to which it may be locked by means of butterfly nuts 26 which engage pins 27 provided on the housing and projecting through slots 28 in the sleeve. By 90 adjusting this sleeve on the housing the length of same may be varied and, therefore, the engagement of the head with the valve adjusted according to the position of the valve in the casing of the cylinder. In cases where the valve 24 is located below the surface I provide grips 29 in the lower end of 95 the sleeve for engaging the opening, normally occupied by the plug, through which the valve is introduced. This permits the locking of the housing to the cylinder casing when grinding.

100 In cases where the valve 24 is flush or above the cylinder casting, as, for example, in the Ford motor, then the sleeve 25 may rest directly on the top of the cylinder, the weight of the device and pressure of the man 110

operating being sufficient for maintaining the same on the cylinder. The engagement of the sleeve with the cylinder prevents the pressure retaining the device on the cylinder 5 from being transmitted to the valve as the stem is yieldable relative to the housing 5 under the action of the spring 19.

To increase the efficiency of the device, an auxiliary spring 30 is provided on the valve 10 which is to be ground. This spring 30 is weaker than the spring 19 but it is sufficient to raise the valve 24 from its seat when a pull is exerted on the ring 23 thereof, compressing the spring 19 and not allowing the 15 valve to disengage from the valve-engaging head 3. As the head is rotated during the forward movement of the stem, the position of the valve relative to its seat will be changed and thereby a better grinding of 20 the seat and valve is obtained.

I claim—

1. In combination, a head for engaging a valve to be ground, a stem movable with the head, a pinion movable with the stem, a 25 housing accommodating the upper end of the stem, a rack slidably mounted in the housing transversely of the stem and engaging the pinion, a disk revolvably mounted in the housing, a wrist pin in said disk, a rod connecting the wrist pin to the rack, an eccentric in said disk carrying said wrist pin whereby the position of said pin relative to the center of the disk may be varied and thereby the throw, and means for rotating 35 the disk.

2. In combination, a telescoping housing, means for adjusting the length of the housing, a head for engaging a valve to be ground, means in one section of the housing 40 for imparting an oscillatory movement to the head, and anchoring means associated with the other section of the housing for

locking the same to a cylinder head substantially as and for the purpose set forth.

3. In combination, an extensible housing, 45 means for varying the length of the housing, a stem mounted to revolve and move longitudinally in the adjustable portion of the housing, a head for engaging a valve to be ground extending out of the housing, a spring normally tending to move the head out of the housing, a pinion constrained to move with the stem, a rack slidably in the housing transversely of the stem engaging the pinion, means for reciprocating the slide, 50 and means whereby the stem may be moved longitudinally while it is reciprocated.

4. In combination, a telescoping housing, means for adjusting the length of the housing, anchoring means at the lower end of one 60 of the housing's parts, said anchoring means being movable transversely of the housing adjustment, a head for engaging a valve to be ground, and means in the other part of the housing for imparting an oscillatory 65 movement to the head.

5. In combination, a head for engaging a valve to be ground, a stem movable with the head, a pinion on said stem, a housing accommodating the upper end of the stem, 70 said stem being revolvable and slidable in said housing, a rack slidably mounted in the housing transversely of the stem and engaging the pinion, a disk revolvably mounted in the housing, a wrist-pin carrier mounted eccentrically at the margin of the disk, means for locking said carrier in predetermined 75 positions, a wrist pin on said eccentric, a rod connecting the wrist pin of the rack, means for revolving the disk, and means whereby the stem may be moved longitudinally without interfering with the oscillation of the 80 stem by the rack.

CHARLES L. LATIMER.
